F. E. WILT

HYDRANT

Original Filed Dec. 28, 1926

Inventor

FRANK E. WILT

By Davis & Davis

Attorney

UNITED STATES PATENT OFFICE.

FRANK E. WILT, OF ZANESVILLE, OHIO.

HYDRANT.

Application filed December 28, 1926, Serial No. 157,497. Renewed March 21, 1928.

The object of this invention is to so construct the parts of a hydrant that the combined inlet-and-waste valve may be withdrawn upwardly from the valve-chamber 5 without unscrewing any part below the surface of the ground or the stand-pipe from the valve-chamber, whereby the valve-washers may be readily renewed from time to time without digging up any of the buried 10 parts of the hydrant, as more fully herein-after set forth.

In the drawing—

Fig. 1 is a vertical sectional view; and Figs. 2, 3 and 4 are horizontal sections on 15 the respective lines indicated in Fig. 1. Referring to the drawing annexed by reference-characters, 5 designates the usual stand-pipe, 6 the valve-chamber screwed to the lower end thereof and having an inlet 20 7 at its bottom and an outlet 8 leading outwardly near its upper end, this outlet being for the purpose of draining the water remaining in the stand-pipe after the inlet-valve is closed. This waste or drain outlet 25 8 is provided with a downwardly-facing valve-seat 9 arranged out of vertical alignment with the central inlet 7. The main inlet-valve 10 is attached to the lower end of a pipe-like rod 11, and the main valve 10 is 30 provided with an offset waste-valve 12 at its upper end which carries washer 13 for closing the waste-valve-seat 9. The main inlet-valve 10 is provided with a washer 14 for closing against the inlet-seat.

The upper end of the valve-rod 11 is screwed into a cylindrical coupling 15, and the upper end of this coupling is swivelly connected to the lower end of a valve-stem 16 which works through a threaded stuffing-box 17 on the upper end of a hollow cast head 18. The hollow head 18 communicates at its lower end with the stand-pipe and at one side it is connected to the delivery-pipe 19 by a detachable coupling 20. The head 40 18 is screwed to the upper end of a sleeve-coupling 21 which in turn is screwed to the upper end of the stand-pipe and forms virtually a part thereof. A guide-bar 22 extends through a transverse slot 23 formed in 45 the coupling 15, the ends of this bar being held down in notches 24 (formed in the upper end of the sleeve-coupling 21) by the head 18 which is provided with a downwardly-facing shoulder 25 which, when the 50 head is screwed in place, abuts against the top of the coupling 21 and the upper face of

the bar 22. A swivel connection between the stem 16 and the coupling member 15 consists of a head 26 formed on the lower end of the stem and adapted to slide laterally 60 into a T-notch formed in the upper end of the coupling.

It will be observed that when the stem 16 is screwed down, the inlet-valve is closed and the waste-valve will be opened, to thereby drain the stand-pipe; and when the main valve is opened, the drain-valve will be closed. The drain-valve is maintained in vertical alignment with the waste-valve seat by means of a guide-lug 27 and also by the 65 guide-bar 22. When it is desired to withdraw the valves upwardly through the stand-pipe for the purpose of repair, I proceed as follows: I first unscrew the coupling 20 to thus permit the head 18 to be unscrewed from its coupling-sleeve 21; this enables the stem 16 to be detached from the coupling member 15. Then the guide-bar is 70 is lifted out of the notches, whereupon the coupling member 15 may be rotated in a direction to carry the waste-valve 12 away from the lug 27. When the waste-valve 12 has thus been rotated to a point from under the downwardly-facing valve-seat 9, as shown in dotted lines in Fig. 1, the valve-rod and attached valves may be lifted 75 entirely out of the stand-pipe, the outlet of the valve-chamber 6 and the internal diameter of the stand-pipe 5 being sufficiently greater than the valve structure, to permit this upward withdrawal of the valve structure. In this way, I avoid the necessity of digging 80 up the stand-pipe and the valve-chamber 6 should the same be buried in the ground.

I have entitled my invention a hydrant, 95 but I do not intend restricting the scope of my invention by using this name, as it will be obvious to those persons having knowledge of the plumbing trade that the invention may be embodied in appliances which 100 are known in the trade by other names; for instance, such devices as are known by the names "street washers", "stop-waste cocks" or "fire hydrants." It will be obvious also that the design may be altered in many ways to suit the needs; for instance, the outlet and inlet may be changed or reversed and the form of the valve may be changed without departing from the spirit of my invention.

What I claim as new is:

1. In a hydrant, a stand-pipe having a valve-chamber attached to its lower end, this

valve-chamber being provided with a bottom inlet having an upwardly-facing valve-seat and also a waste-outlet provided with a downwardly-facing valve-seat, a valve-rod depending into said valve-chamber and carrying a valve-means comprising a downwardly-facing inlet-valve and an upwardly-facing waste-valve, means on the upper end of the stand-pipe for reciprocating said valve-rod, these means embodying devices which permit the valve-rod to be rotated sufficiently to bodily swing the waste-valve laterally from under the waste-valve-seat, to thereby permit the valve-rod and valves to be moved upwardly through the stand-pipe, the diameter of the outlet of the valve-chamber and the internal diameter of the stand-pipe being greater than the diameter of the valve-means, to permit said upward withdrawal of the valves.

2. In a hydrant, a stand-pipe having a valve-chamber attached to its lower end, this valve-chamber being provided with a bottom inlet having an upwardly-facing valve-seat and also a waste-outlet provided with a downwardly-facing offset valve-seat, a valve-rod depending into said valve-chamber and carrying a valve-means comprising a downwardly-facing inlet-valve and an offset upwardly-facing waste-valve, means on the upper end of the stand-pipe for reciprocating said valve-rod, these means embodying guide-means for the valve-rod and a removable head which when in place locks the guide-means in assembled relation and which when removed from the stand-pipe permits the valve-rod to be rotated for the purpose set forth, said stand-pipe and the outlet of said valve-chamber having a greater diameter than said valve-means.

3. In a hydrant, a stand-pipe having a valve-chamber attached to its lower end, this valve-chamber being provided with a bottom inlet having an upwardly-facing valve-seat and also a waste-outlet provided with a downwardly-facing offset valve-seat, a valve-rod depending into said valve-chamber and carrying a valve-means comprising a downwardly-facing inlet-valve and an offset upwardly-facing waste-valve, means on the upper end of the stand-pipe for reciprocating said valve-rod, these means embodying a hollow head detachably connected to the upper

end of the stand-pipe, this head being provided with a lateral discharge-nipple and means for detachably coupling it to the delivery-pipe, a screw valve-stem working down through the head, a guide-coupling swivelly connected to said stem and extending down into the stand-pipe, this guide-coupling being provided with a transverse slot, and a guide-bar having its ends held in place by said head, said stand-pipe and the outlet of said valve-chamber having a greater diameter than said valve-means.

4. In an apparatus of the class set forth, a valve-chamber having an offset inlet and a waste-outlet and also a main-outlet, a stand-pipe attached to the main-outlet of said valve-chamber, a valve-rod extending down through the stand-pipe and into the valve-chamber and provided with a valve for said inlet and also an offset valve for said waste-outlet, the outlet of said valve-chamber and the diameter of the stand-pipe being such as to permit the valve-rod carrying the valves to be lifted up through the same, and means on top of the stand-pipe for operating said valve-rod to alternately open and close said inlet and said waste-outlet.

5. In an apparatus of the class set forth, a valve-chamber having an inlet and a waste-outlet and a main-outlet, said inlet and said waste-outlet facing in opposite directions, a stand-pipe attached to the outlet of said valve-chamber, a valve-rod extending down through the stand-pipe and into the valve-chamber and carrying two valves, one for the waste-outlet and the other for the inlet, the diameter of said main-outlet and the stand-pipe connected thereto being such as to permit the valves to be raised up through the stand-pipe, means mounted on the top of the stand-pipe for raising and lowering the valve-rod embodying a removable head, these means embodying devices which permit the valve-rod to be rotated sufficiently to bodily swing the waste-valve laterally from under the waste-outlet, and guiding means for the valve-rod adapted to be released when said head is detached from the stand-pipe to thereby permit the valve-rod to be rotated for the purpose set forth.

In testimony whereof I hereunto affix my signature.

FRANK E. WILT.
